F. WEVER

FEATHER FEEDING DEVICE

Original Filed May 15, 1922 2 Sheets-Sheet 2

UNITED STATES PATENT OFFICE.

FRITZ WEVER, OF STUTTGART, GERMANY; HENRI MARMIGNAT ADMINISTRATOR OF
SAID FRITZ WEVER, DECEASED.

FEATHER-FEEDING DEVICE.

Original application filed May 15, 1922, Serial No. 561,216, and in Germany December 14, 1920. Divided
and this application filed June 24, 1924. Serial No. 722,187.

This is a division of my co-pending application, filed May 15th, 1922, Serial No. 561,216, for improvements in making fur or plumage like material.

This invention relates to the art of making fur or plumage like material, and in particular such material as is made by securing feathers to supporting layers of sheet material, such as cloth or other textiles. Such material is adapted for use for cloaks, over-coats and garments of other descriptions, for covers, in general, and for all of the uses to which furs are applied, and it may be applied as an interior lining or an exterior covering.

The invention is designed to furnish means whereby the feathers or similar material are secured in a uniform and even layer to a layer of supporting material, preferably textile material, and in such a way that the operation of securing the feathers may be done expeditiously and with accuracy.

With these objects in view, my invention comprises means for advancing feathers in successive quantities to a sewing or other securing mechanism and at the same time feeding a band or strip of textile or other sheet material to the said securing means, the parts being so arranged that the feathers are spread in a flat, even and uniform layer onto the band or strip in successive quantities at a rate of speed conforming to the speed of the sewing or other attaching mechanism. To facilitate and aid this action I also provide means for loosening the feathers and preventing their agglomeration or tendency to stick together in lumps such means being arranged at a point behind the conduit through which the feathers are passed to the attaching mechanism.

My invention, moreover, comprises details of construction and arrangement, and such other features, methods, means and combinations of parts as will be hereinafter set forth and more particularly pointed out in the claims forming part of this specification.

In the accompanying drawings, I have represented an apparatus which I consider the preferred embodiment of my invention.

In these drawings:

Figure 1 represents a vertical section of such apparatus;

Fig. 2 a plan view thereof;

Fig. 3 a plan view of the compressed air duct or pipe of same, showing the exhaust mechanism;

Fig. 4 a detail view in sectional side elevation of said mechanism; and

Fig. 5 a detail view in front elevation of the stripping and advancing parts.

The apparatus shown is particularly adapted for treating the heavier sorts of feathers, such as wing feathers, which require no preliminary loosening or separating action. As shown, it is arranged to directly adjoin the table of the sewing mechanism, 13, 14.

In the drawing, 1 represents the supply hopper or holder through which the feathers are introduced into the apparatus. The lower end or outlet 1^c of the hopper 1 is furnished with a device for retaining the feather charge and for withdrawing the feathers in small quantities to be successively delivered for further treatment by the apparatus. This device comprises a series of longitudinal ribs 1^b, preferably arranged on the wall of the hopper, which lies between the walls on which the ribs 1^a are formed, a roller 2 provided with picker needles 2^a, and a roller 3 provided with stripping forks 3^a arranged below and adjacent to the picker needle roller 2 and in such position that the forks will straddle or engage the picker needles 2^a as they pass the stripping fork roller, and that said fork will just clear the lower edges of the ribs 1^b. As shown, the ribs 1^b have a curved contour corresponding to the path of the picker needles 2^a.

The picker needle roller 2 and the stripping fork roller 3 are caused to rotate in the direction indicated by the arrows in Fig. 1; that is to say, so that as the picker needles 2^a move downward and outward, the stripping forks which engage or straddle these needles as best seen in Figure 5, move inward and upward past the lower corners of the ribs 1^b, thus stripping the feathers in contact with the picker needles 2^a from them and past the ribs 1^b.

The picker needles, besides their rotary movement, have a radially reciprocating motion and so as to advance as they enter the hopper, and then to be retracted as they leave the hopper, said reciprocating movement being imparted to them by a cam groove 2^b, indicated in Fig. 1, the needles 2^a being also radially guided by studs thereon engaging radial slots 2^c of the needle supports. The details of the needle reciprocating device being already disclosed in my United States Patent No. 1,483,703, issued February 12, 1924, and in my German Patent No. 330,444, issued December 14, 1920, and not constituting per se a part of my present invention, need not be described in further detail herein.

The lower portion of the hopper is provided with slots 1^d, Figs. 1 and 5, to permit the entrance of the picker needles 2^a into the hopper.

The feathers as they reach the bottom of the hopper 1, are grasped by the forked strippers 3^a of the stripper shaft and carried therefrom to the nozzle 11, by a blast or blasts of compressed air. For this purpose there is arranged at 40 an air compression pump or blower, the air from which passes through pipe 41, which is connected to the outlet of the compression-pump, to the mouthpiece comprising in the present instance a plurality of jet orifices 42 (see Figs. 2 and 3) arranged behind the withdrawing means, that is to say, the strippers 3^a, in their forward position. Thereby the jet-orifices 42 serve to blow the feathers from the forks 3^a into and through the mouthpiece 11 toward the arresting prongs 11^a and the picker needle roller 12, where they are further operated on in the manner hereinafter described. The air pipe 41 is provided with an air cock 43, by which the rate or quantity of air discharged into said pipe may be regulated, the regulating operation being guided by a scale 48 and a pointer 49 arranged to travel over said scale and mounted on the plug of the cock. In order to discharge the air from the jet orifices in intermittent streams or gusts, the pipe 41 is furnished with a reciprocating slide valve 44, Figs. 1 and 4, to alternately open and shut off said pipe, said slide 44 being raised to the dotted line position, Fig. 4, and thus opened, by a cam or tappet wheel 46 bearing on one arm of a rock lever 45 fulcrumed at 451, the other arm of which is connected to said slide 44 by link 441, and thereupon quickly lowered to shut off the pipe by a spring 461 arranged to draw the lever against cam or tappet wheel 46. In order to discharge the compressed air from the pipe 41 when the slide valve is lowered and closed, and thereby to eliminate injurious back pressure on the compression pump or blower,

a flap valve or vent 47 is arranged on the pipe 41 behind the slide valve 44, said flap valve being operated from the rock lever 45 by the connecting rod 471, connected to said rock lever and the flap valve, as seen in Figs. 1 and 4. From the arrangement thus shown it will be seen that the flap valve will open when the pipe 41 is shut off by the slide 44, and shut when it is open.

The forward end of the nozzle 11 is provided at its forward end or mouth with the arresting prongs 11^a of resilient material which are preferably arranged in staggered relation to the lower series of ribs 11^b arranged on the bottom of the interior of the nozzle. These prongs co-operate with the ribs 11^b to form a yielding feather retaining device. By these means the feathers as they are blown in allotments into the nozzle 11 are arrested until they are released by the mechanism described below.

A sewing mechanism comprising the presser foot 13 and needle bar 14 is arranged in advance of the mouth piece or nozzle 11, Figs. 1 and 2. Between said sewing mechanism and the nozzle 11 is arranged the feather picking mechanism for releasing successive quantities of feathers from the arresting prongs 11^a and feeding them onto a strip of feather supporting material 15 which is fed to the machine in any desired manner from a web or roller. This feather picking mechanism consists of a roller 12 provided with radial picker needles 12^a arranged thereon, as seen in Fig. 1. These picker needles are so arranged as to enter the slots between the prongs 11^a as the roller revolves, and to withdraw the feathers held against said prongs by the air current, dropping them onto the band or strip 15 on which they are fed to the needle 14^a and under the presser foot 13, as seen in Fig. 1.

What I claim and desire to secure by Letters Patent is:

1. In an apparatus of the character set forth, a holder for feathers or similar material, attaching means for securing the feathers to a supporting layer and means for withdrawing successive quantities from the holder, in combination with a conduit leading from the feather withdrawing means to the attaching means, and means arranged behind the withdrawing means for blowing the feathers from the said withdrawing means to the attaching means.

2. In an apparatus of the character set forth, mechanism for securing feathers to a supporting layer, a holder for feathers or similar material having an outlet portion, a series of rotary picker needles arranged to enter and travel past the outlet portion and a series of rotary stripping forks arranged to travel past and to strip the feathers from the picker needles, in combination with a conduit extending from the

stripping forks toward the attaching mechanism, a blast mechanism comprising nozzles so arranged within the conduit as to blow the feathers or attaching material from the stripping forks and into and through the conduit toward the attaching mechanism.

3. In an apparatus of the character set forth, a holder for feathers or similar material, attaching means for securing the feathers to a supporting layer and means for withdrawing successive quantities of feathers from the holder, in combination with a conduit leading from the feather withdrawing means to the attaching means, and means arranged behind the withdrawing means for intermittently blowing the feathers from said withdrawing means to the attaching means.

20 4. In an apparatus of the character set forth, mechanism for securing feathers or similar material to a supporting layer, a holder for such material having an outlet portion, and means for withdrawing successive quantities of feathers from the holder, in combination with a conduit leading from the feather withdrawing means to the feather securing mechanism, an air compression pump, and a jet-orifice or orifices communicating with the pump and so arranged within the conduit as to blow the feathers from the point where they are withdrawn from the holder, and means to alternately open and close the communication between the pump and the jet orifices, whereby an intermittent blast is created through the conduit and behind the feathers as they are withdrawn from the holder.

5. In an apparatus of the character set forth, a holder for feathers and similar material, means for withdrawing successive portions of the material from the holder, and a conduit for the passage of the material to means for securing the material to a support, in combination with an air compression pump and a jet orifice or orifices arranged to blow the feathers from the point where they are withdrawn from the holder, a pipe for the compressed air pump

connecting the outlet of said pump with 50 the orifice or orifices, a valve arranged in the compressed air pipe, and means for alternately opening and closing the valve.

6. In an apparatus for conveying feathers and like material, a receptacle for the material having an outlet, and means at the outlet for withdrawing the material in successive quantities from the said receptacle, in combination with a pipe for compressed air having an air outlet or outlets arranged to 55 blow the feathers from the feather withdrawing means, means for forcing air through the compressed-air pipe, a valve for periodically closing the compressed air pipe, and a valve arranged to open the portion of the pipe behind said first valve at each closing 60 of the first-named valve, both valves being arranged in the compressed-air pipe.

7. In an apparatus of the character set forth, a conduit for feathers or similar material, in combination with an air compression pump, a pipe leading therefrom into the conduit and terminating in a jet-orifice or orifices, a valve arranged on said pipe, means for alternately opening and 70 closing said valve to produce intermittent blasts from the orifices or orifices, and a vent and means connected therewith to open and close the same as the valve is respectively closed and opened.

8. In an apparatus of the character set forth, a holder for feathers or similar material, attaching means for securing the material to a supporting layer, and means for withdrawing successive quantities of 75 feathers from the holder, in combination with a conduit leading from the withdrawing means to the attaching means, means for blowing the material from the withdrawing means to the attaching means, the forward end of the conduit being provided with a yielding retaining device and a feather picking device arranged to engage with said retaining device being located behind the attaching device.

In testimony whereof, I affix my signature.

FRITZ WEVER.

CERTIFICATE OF CORRECTION.

Patent No. 1,599,387,

granted September 7, 1926.

to FRITZ WEVER, deceased, whose Administrator is HENRI MARMIGNAT.

It is hereby certified that error appears in the printed specification of the above mentioned patent requiring correction as follows: Page 1, in the heading to the printed specification, line 6, date of filing application in Germany, for December 14, 1920 read June 30, 1921; and that the said Letters Patent should be read with this correction therein that the same may conform to the record of the case in the Patent Office.

Signed and sealed this 22nd day of February, A. D. 1927.

Seal.

M. J. Moore,
Acting Commissioner of Patents.
